FIG. 1

FIG. 2

FIG. 3

FIG. 1 a front perspective view of a camera showing my new design;

FIG. 2 is a rear perspective view thereof; and

FIG. 3 is a view similar to FIG. 1 but showing the flashgun in open or operative condition.

The bottom of the camera, not shown, is substantially plain and unornamented.

The broken-line showing of a flashbulb in FIG. 3 is for illustrative purposes only.

I claim:

The ornamental design for a camera, as shown and described.
